CLAIM

The ornamental design for a whiskey bottle, as shown and described.

DESCRIPTION

FIG. 1 is a front and side perspective view of the whiskey bottle of the present invention;
FIG. 2 is a rear elevational view thereof;
FIG. 3 is a left-side elevational view thereof;
FIG. 4 is a right-side elevational view thereof;
FIG. 5 is a top plan view thereof; and
FIG. 6 is a bottom plan view thereof; and,
FIG. 7 is a top and side perspective view thereof.
The broken line showing is for illustrative purposes only,
and forms no part of the claimed design.
